UNITED STATES PATENT OFFICE.

JACOB H. PRESS, OF CHICAGO, ILLINOIS.

DESIGN FOR A VEHICLE-BODY.

52,964.

Specification for Design.

Patented Feb. 4, 1919.

Application filed November 10, 1917. Serial No. 201,388. Term of patent 14 years.

To all whom it may concern:

Be it known that I, JACOB H. PRESS, a citizen of the United States, residing at Chicago, in the county of Cook and State of Illinois, have invented a new and original ornamental Design for Vehicle-Bodies, of which the following is a specification, reference being had to the accompanying drawing, forming part thereof.

Figure 1 is a perspective view of a vehicle body, showing my new design;

Fig. 2 is a rear end elevation of the same.
I claim:

The ornamental design for a vehicle body, as shown.

JACOB H. PRESS.
